UNITED STATES PATENT OFFICE.

EMIL LUNDQVIST, OF PITTSBURG, PENNSYLVANIA.

TRAVELING CONTACT DEVICE.

SPECIFICATION forming part of Letters Patent No. 592,150, dated October 19, 1897.

Application filed October 28, 1896. Serial No. 610,319. (No model.)

To all whom it may concern:

Be it known that I, EMIL LUNDQVIST, a subject of the King of Sweden and Norway, residing at Pittsburg, in the county of Allegheny and State of Pennsylvania, have invented certain new and useful Improvements in Traveling Contact Devices; and I do hereby declare the following to be a full, clear, and exact description of the invention, such

as will enable others skilled in the art to which it appertains to make and use the same.

My invention relates to improvements in a traveling contact device or trolley for electric railways, traveling cranes, canal-boats, and other electrically-propelled vehicles where the working current is obtained from a conductor extending along the line of travel.

The object of my invention is to provide a rolling contact that combines two properties essential for successful operation of devices to which my invention relates: first, the establishing of a large contact-surface between the working conductor and the traveling contact device, and, secondly, the provision of an elastic cushion between the conductor and the rigid body of the traveling contact device in order to reduce the liability of the contact device to jump from the conductor and break the contact therewith. Having this object in view, I provide a rolling contact that will, when maintained against the conductor, establish a contact-surface between the conductor and the traveling contact device that has an area great enough to permit a very large current to pass from the conductor to the point desired. This I accomplish by using an elastic ring or endless flexible belt, made of electric conducting material, said ring maintained in contact with the conductor and caused to roll against the same in such a manner that two or more separated surface lines or points on the ring are pressed against the conductor, and owing to the elasticity of the ring and to suitably-provided means intermediate points or lines on the surface of the ring are also in contact with the conductor, all as more fully hereinafter described.

My invention is illustrated in the accompanying drawings, in which—

Figure 1 is a side view in elevation; Fig. 2, a sectional view; Fig. 3, a plan view of part

of ring, and Fig. 4 a sectional detail view of ring.

Referring to the drawings, A designates an elastic ring made of any material that combines the essential qualities of conductivity of electricity and elasticity, such as spring-steel or phosphor-bronze. The ring may be composed of a single substance or built up of several substances.

B' is a trolley-wheel rotatively mounted on an axle C', resting in the sides of the fork H, carried on the upper end of a trolley-pole or other suitable frame that may be employed for supporting the contact device. The wheel B' is provided with a series of separated recesses D, located on both sides of the groove of the wheel and in a circle having its center in the center of the wheel-axle C'.

S are radial spokes, the purpose of which is to keep the conductor as near the middle of the elastic ring A as possible and thereby diminish the friction between the conductor and the sides of the grooved portion of the wheel. The elastic ring A is placed on the wheel B' in the groove of the said wheel and is provided with projections P, which correspond in number and shape to the recesses D, and are designed to fit over and be supported in the recesses. The body of the ring acts as a cushioned or elastic tire for the trolley-wheel.

It will be obvious that modifications in the form and arrangement of the elastic ring and the recesses and other essential elements of my traveling contact device herein shown and described may be made without departing from the important features of the invention. Thus the recesses in the wheel may be made continuous instead of broken or separated recesses, as above described, and the continuous elastic ring may be made without the projections P. In case it may be desirable to employ continuous recesses in the wheel B', then the ring A need not be provided with projections, but will rest directly in the recesses.

It is usually desirable to provide the ring A with a supplemental ring or band K, made of some good flexible electric conducting material. This supplemental ring K bears directly against the conductor, so that wear on the elastic ring A is prevented and when the contact-surface is worn out it is only neces-

sary to replace it by putting in a new contact-surface K. As the diameter of the ring A is less than the diameter of the sides of the wheel, it is necessary to have one or both flanges removably secured to the wheel-hub, by means of bolts, screws, or other suitable means. In the drawings, the flange R is shown as being removable. Owing to the fact that the diameter of the elastic ring A, or rather its outer diameter, is a little less than the diameter of the circle in which the recesses D are located, the ring is loosely mounted in said recesses. Consequently when the ring is not pressed against the conductor it will rest on the lowest point of the recesses, but when the pressure of the frame that carries the trolley-wheel forces the wheel up against the conductor, that part of the elastic ring which is next to the conductor will be pressed toward the center of the wheel, while the remaining part is forced to conform to the shape of the recesses. The strength of the elastic ring is so fixed that after a certain amount of depression the resistance of the ring will equal the external pressure and at the same time the depressed part of the ring is flattened out on the conductor. This flat portion of the ring constitutes the current-transmitting surface between the conductor and the trolley. The path of the current taken off the conductor is from the ring, through the recesses D, to the hubs of the wheel and then by means of sliding contacts to the wiring of the vehicle.

It will be noticed that owing to the construction above described the elastic ring will roll along the conductor always presenting a considerable length of contact-surface to the conductor. This construction secures at the same moment many contact-points between the conductor and the ring, and each and every contact-point on the contact-surface of the ring remains stationary, relatively to the conductor, for a time, fixed by the distance between the extreme points of that part of the ring at the time being in contact with the conductor. It will be further seen that I have provided an elastic or cushioned tire between the conductor and the rigid body portion of the contact device or trolley-wheel.

Having thus described my invention, what I claim is—

1. In a traveling contact device, in combination with a conductor, a wheel, having recesses concentric with the axle of the wheel;

an elastic continuous ring, of suitable electric conducting material, on said wheel and supported by the walls of said recesses; means for pressing said wheel against said conductor whereby when the wheel is forced against the conductor that part of the ring so pressed will be forced toward the center of the wheel while the remaining part of the ring is conformed to the said recesses, substantially as described.

2. In a traveling contact device, a wheel, having recesses concentric with the axle of the wheel; an elastic continuous ring, of suitable electric conducting material supported by the walls of said recesses, substantially as described.

3. In a traveling contact device, a wheel, provided with a groove and having recesses concentric with the axle of the wheel on both sides of the groove; spokes between said recesses; an elastic continuous ring, of suitable electric conducting material supported by the walls of said recesses, substantially as described.

4. In a traveling contact device, a wheel, provided with a groove and having recesses concentric with the axle of the wheel on both sides of said groove; spokes between said recesses; an elastic continuous ring, of suitable electric conducting material in said groove, said ring having projections supported by the walls of said recesses, substantially as described.

5. In a traveling contact device, a grooved wheel, having recesses concentric with the wheel-axle; an elastic continuous ring, of suitable electric conducting material in said groove and supported by the walls of said recesses; said wheel provided with removable flanges, substantially as described.

6. In a traveling contact device, a wheel, having recesses concentric with the axle of the wheel; an elastic continuous ring of suitable electric conducting material supported by the walls of said recesses, said ring provided with a supplemental ring of good wearing and electric conducting material, substantially as described.

In testimony whereof I affix my signature in presence of two witnesses.

EMIL LUNDQVIST.
